(57) **CLAIM**

The ornamental design for a flip earring, as shown and described.

DESCRIPTION

FIG. 1 is a perspective view of a flip earring showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back perspective thereof.

The broken lines shown illustrate portions of the flip earring and form no part of the claimed design.
